UNITED STATES PATENT OFFICE.

CHARLES F. McCRORY, CHARLES P. McCRORY, AND HAROLD PALLISER, OF JOHNS-TOWN, PENNSYLVANIA; SAID PALLISER ASSIGNOR TO SAID CHARLES F. McCRORY AND SAID CHARLES P. McCRORY.

DESIGN FOR A TOY FENCE.

Application filed June 9, 1926. Serial No. 18,000. Term of patent 14 years.

To all whom it may concern:

Be it known that we, CHARLES F. McCRORY, CHARLES P. McCRORY, and HAROLD PALLISER, citizens of the United States, residing at Johnstown, in the county of Cambria and State of Pennsylvania, have invented a new, original, and ornamental Design for Toy Fences, of which the following is a specification, reference being had to the accompanying drawing, forming part thereof.

The figure is a perspective view of the fence constructed in accordance with the present invention.

We claim:

The ornamental design for a toy fence, as shown.

CHARLES F. McCRORY.
CHARLES P. McCRORY.
HAROLD PALLISER.
